UNITED STATES PATENT OFFICE.

CHARLES W. ERVIN, OF LOS ANGELES, CALIFORNIA.

CAN OPENER.

Application filed February 23, 1922. Serial No. 538,593.

To all whom it may concern:

Be it known that I, CHARLES W. ERVIN, a citizen of the United States, residing at Los Angeles, in the county of Los Angeles and 5 State of California, have invented a new and useful Can Opener, of which the following is a specification.

This invention relates to devices for opening receptacles, normally hermetically closed 10 for preserving the inclosed matter, as canned food-articles.

One of the objects of this invention is to provide a device that will automatically move along the edge of a can when applied 15 and operated.

Another object is to provide a device with handles similar to the handles of pliers, pincers, or shears, to be operated in a plane parallel to the top of a can on which the device is to be used, having a cutting member 20 to cut and project through the top of the can.

Another object is to provide a cutting member in one arm of the device and a gripping member in the other arm of the device, so that the cutting member will be drawn towards the gripping member by a closing of 25 the device.

Another object is to provide means for 30 automatically opening the device and thereby advancing the gripping arm ahead of the cutting arm.

Other objects will appear from the following description and appended claims as 35 well as from the accompanying drawing, in which—

Fig. 1 is a top plan view of the device, a portion of the circular top edge of a can being indicated in dotted lines to illustrate 40 the relative position of the device when applied to a can.

Fig. 2 is a fragmentary section on line 2—2 of Fig. 1.

Fig. 3 is a fragmentary section on line 45 3—3 of Fig. 1.

Fig. 4 is a fragmentary top plan view of a slightly modified form of the device, one end of the spring being directly connected to the gripping arm of the device, to produce a more positive disengagement for forwarding the gripping member ahead of the cutting member.

In Fig. 1, the cutting means are provided 55 on the handle 5, and the gripping means are provided on the handle 6. The member, indicated at 7, may broadly be termed the

common pivot for the handles 5 and 6. All parts on one side of the pivot 7, embodying the handle 5, may hereafter be called the cutting arm. All parts on the other side of 60 the pivot 7, embodying the handle 6, may hereafter be called the gripping arm. A spring 8 is inserted between the two arms, so that the one end 9 of the spring engages with the cutting arm and the end 10 of the 65 spring engages with the gripping arm, for normally holding the two arms apart. A cutting blade 11 is provided on the underside of the cutting arm 5. Spaced from cutting blade 11, also on the underside of the 70 cutting arm 5, a guiding shoulder-member 12 is provided so as to normally project over the outside of a can, for guiding the cutting blade 11 in cutting along the edge of the can.

The top of a can is indicated at 13 in Fig. 75 2, showing the cutting blade 11 punched through the top. The edges of the tops of cans are normally rolled over the sides 14, as indicated at 15. The shoulder member 12 can then easily slide along the outside of 80 the can so as to guide the cutting blade 11 at an even distance from the edge along the edge of the can.

The cutting blade may be spaced more or less from the shoulder member 12, to make 85 this device applicable to differently constructed cans and to satisfy different requirements and desires of the users. In spacing the cutting blade as little as possible from the shoulder member 12, the cut 90 edge can be practically rolled towards the inner surface of the side 14, as indicated at 16, so as to avoid the rough edges in the openings of opened cans and thereby make 95 injury practically impossible, which is otherwise of such common occurrence with opened cans.

The gripping arm is preferably made in sections, pivotally interconnecting, as at 17. A shoulder member 18 is provided on the 100 base portion 19 of the gripping arm, normally to engage the rim of a can along the inner circle, see Fig. 1, and as also illustrated in detail in section in Fig. 3. The handle portion 6 of the gripping arm is provided with an extension end 20 beyond the pivot 17, for engaging the rim of a can 105 from the outside opposite the shoulder member 18.

Moving or swinging the handle portion 6 110 of the gripping arm around the pivot 17 in the direction towards the other handle 5,

2
the extension end 20 moves towards the edge of the cam, when so applied. Pressing the handles further in the direction towards each other, the gripping arm being locked to the edge or rim of the can as soon as the extension end 20 touches the rim, the cutting arm is compelled to move towards the gripping arm, thereby causing the cutting blade to cut through the top of the can along the rim as guided by the shoulder member 12 on the cutting arm.

Having the handles pressed towards each other, on releasing the handles, the cutting arm being held in its position by reason of its cutting blade sticking or binding in the cut made by it in the top of the can, the spring 8 causes the gripping arm to swing away from the cutting arm thereby advancing along the rim of the can.

20 On again touching the handles the operation of cutting and pressing the handles towards each other is repeated.

The spring serving for advancing the device along the rim of a can, the device works itself around the rim of a can by the mere repeating of the pressing of the handles. It is not necessary to move the can. The device holds itself to the can and moves the can according to the movements made by the cutting blade and the advancing of the gripping arm after each cut. The can may be placed on the table or on a suitable surface so that the device can be applied.

In Fig. 4, the slightly modified form illustrates the one end 21 of the spring 8 extended to engage directly with the handle 6, as indicated at 22.

The arrangement serves to disengage the extension end 20 more readily than under the arrangement of Fig. 1.

In Fig. 1, the spring acts on the arms close to the main pivot 7. A slight pressing on the handle 6 causes a friction of the extension end 20 on the rim of a can.

45 In Fig. 4, the spring acts on the handle 6, thereby tilting the handle around its pivot 17 as soon as the handle 6 is released, and tends to free the extension end 20 more than under the arrangement in Fig. 1.

50 The extension end 20, nor the handle 6, under the arrangement in Fig. 1, are under no direct influence of the spring, and therefore are not liable to free the rim of a can so well as under the arrangement of Fig. 4.

55 A stop 23 is provided for the handle 6 to limit the movement of the lever, and especially the extension end 20, so that the extension end is maintained in a position to be moved quickly into engaging position.

Having thus described my invention, 60 I claim:

1. In a can opener, a cutting arm and a gripping arm pivotally connected at one of their ends, a spring inserted between the two arms for normally holding the arms 65 spaced, cutting means on the underside of the cutting arm spaced from the pivot connection, and gripping means on the underside of the gripping arm spaced from the pivot connection and disposed so that an 70 engagement of the gripping arm on the edge of a can may serve to allow a drawing of the cutting means on the cutting arm in the direction towards the gripping arm through the top of the can along the same 75 edge of the can.

2. In a can opener, a cutting arm and a gripping arm having pivot connection, the cutting arm having cutting means projecting towards one side spaced from the point of the pivot connection, the gripping arm being made in sections having pivot interconnection, a shoulder member on one section of the gripping arm at a point spaced from the common pivot connection between the first-named two arms to nearly the same extent as the spacing between the cutting means on the cutting arm and the pivot connection on the cutting arm, an extension end on the second section of the gripping arm projecting sidewise from the pivot connection within the gripping arm in the direction towards the cutting arm so as to form a cam-like member to co-act with the shoulder member for drawing the cutting arm 95 towards the gripping arm.

3. In a can opener, a cutting arm having cutting means on its underside, a gripping arm made in sections, one of the sections being pivotally connected to the cutting arm, the second of said sections being pivotally connected to the first-named section forming cam-like engaging means between the two sections, and a spring inserted between the arms for normally holding the arms spaced with the cutting means pointing in the direction of the cam-like engaging means and adapted to advance the gripping arm ahead of the cutting means after each contraction of the arms.

100 In testimony that I claim the foregoing as my invention I have signed my name in the presence of two subscribing witnesses.

CHARLES W. ERVIN.
